(57) **CLAIM**

The ornamental design for a transaction card, as shown and described.

DESCRIPTION

FIG. 1 is a front isometric view of a transaction card according to a first exemplary embodiment of the present invention;

FIG. 2 is a front elevation view thereof;

FIG. 3 is a top plan view thereof;

FIG. 4 is a bottom plan view thereof;

FIG. 5 is a left side elevation view thereof;

FIG. 6 is a right side elevation view thereof; and

FIG. 7 is a rear elevation view thereof.

FIG. 8 is a front isometric view of a transaction card according to a second exemplary embodiment of the present invention;

FIG. 9 is a front elevation view thereof;

FIG. 10 is a top plan view thereof;

FIG. 11 is a bottom plan view thereof;

FIG. 12 is a left side elevation view thereof;

FIG. 13 is a right side elevation view thereof; and

FIG. 14 is a rear elevation view thereof.

FIG. 15 is a front isometric view of a transaction card according to a third exemplary embodiment of the present invention;

FIG. 16 is a front elevation view thereof;

FIG. 17 is a top plan view thereof;

FIG. 18 is a bottom plan view thereof;

FIG. 19 is a left side elevation view thereof;

FIG. 20 is a right side elevation view thereof; and

FIG. 21 is a rear elevation view thereof.

(Continued)

FIG. 22 is a front isometric view of a transaction card according to a fourth exemplary embodiment of the present invention;

FIG. 23 is a front elevation view thereof;

FIG. 24 is a top plan view thereof;

FIG. 25 is a bottom plan view thereof;

FIG. 26 is a left side elevation view thereof;

FIG. 27 is a right side elevation view thereof; and

FIG. 28 is a rear elevation view thereof.

FIG. 29 is a front isometric view of a transaction card according to a fifth exemplary embodiment of the present invention;

FIG. 30 is a front elevation view thereof;

FIG. 31 is a top plan view thereof;

FIG. 32 is a bottom plan view thereof;

FIG. 33 is a left side elevation view thereof;

FIG. 34 is a right side elevation view thereof; and

FIG. 35 is a rear elevation view thereof.

FIG. 36 is a front isometric view of a transaction card according to a sixth exemplary embodiment of the present invention;

FIG. 37 is a front elevation view thereof;

FIG. 38 is a top plan view thereof;

FIG. 39 is a bottom plan view thereof;

FIG. 40 is a left side elevation view thereof;

FIG. 41 is a right side elevation view thereof; and

FIG. 42 is a rear elevation view thereof.

FIG. 43 is a front isometric view of a transaction card according to a seventh exemplary embodiment of the present invention;

FIG. 44 is a front elevation view thereof;

FIG. 45 is a top plan view thereof;

FIG. 46 is a bottom plan view thereof;

FIG. 47 is a left side elevation view thereof;

FIG. 48 is a right side elevation view thereof; and

FIG. 49 is a rear elevation view thereof.

The broken line showing of the transaction card is for the purpose of illustrating portions of the transaction card and forms no part of the claimed design.
